UNITED STATES PATENT OFFICE.

MICHAEL LA ROCCO, OF CHICAGO, ILLINOIS, ASSIGNOR OF ONE-HALF TO JAMES F. BOWAN, OF CHICAGO, ILLINOIS.

TERMINAL-PROTECTOR.

1,315,135.

Specification of Letters Patent.

Patented Sept. 2, 1919.

Application filed March 15, 1919. Serial No. 232,880.

To all whom it may concern:

Be it known that I, MICHAEL LA Rocco, a citizen of the United States, residing at Chicago, in the county of Cook and State 5 of Illinois, have invented new and useful Improvements in Terminal-Protectors, of which the following is a specification.

This invention relates to storage battery terminals and its object is to provide a novel 10 and improved shield for the terminals to protect the same from the corroding influences of the acid and fumes of the battery, and furthermore, to provide a shield for this purpose which is simple and inexpensive, 15 and which can be very readily applied or removed.

In order that the invention may be better understood, reference is had to the accompanying drawing, forming a part of this 20 specification, and in said drawing,

Figure 1 is a perspective view of the device, prior to its application to the terminal;

Fig. 2 is a plan view showing how the device is folded for application to the 25 terminal;

Fig. 3 is a horizontal cross section of the device on the terminal;

Fig. 4 is a central longitudinal section of the device as shown in Fig. 1, and

30 Fig. 5 is a perspective view of the terminal to which the device is applied.

Referring specifically to the drawing, 10 denotes a fragment of a storage battery element having an upstanding post 11 carrying 35 a head 12, the latter having a vertical aperture to slip down over the post, on which it is permanently secured by being soldered, as shown at 13. The head 12 also has a transverse, horizontal aperture to seat 40 a tapered plug 15 projecting from one side of the head, and held in place on the opposite side by a cap screw 16 screwed into the corresponding end of the head, as shown in Fig. 3. The projecting end of the plug is 45 apertured for connection with the wire 17, the same being embedded in solder 18 filling the aperture.

The terminal disclosed is of conventional construction, and as nothing is claimed 50 therefor, a further description thereof is not deemed necessary.

The protecting device is molded or otherwise constructed out of rubber or other suitable material adapted for the purpose for 55 which the device is designed, and it is also

pliable so that it may be bent as will be presently described. As shown in Fig. 1, the device comprises a plain, flat medial strip 19 having cylindrical heads 20 and 21, respectively, at its ends. These heads are on the same side of the strip and they project laterally therefrom. The head 20 is tubular, its bore being open at both ends. The head 21 is also tubular, but its bore is closed at the outer end of the head. The ends of the strip, on the side opposite the side from which the heads project, have outstanding marginal flanges 23 and 24, respectively. The flanges extend in a curve around the ends of the strip and at their ends they extend with a curve down to the medial portion of the strip 19. It will also be noted that the flanges are spaced from each other so as to leave the medial portion of the strip plain and flat, and entirely devoid of projecting parts.

To apply the device shown in Fig. 1 to the battery terminal, it is bent at its ends in a direction to bring the flanges 23 and 24 together in edgewise contact, and the heads 20 and 21 in longitudinal alinement as shown in Fig. 2. Before doing this, the device is so positioned with respect to the terminal that when it is bent around the same the head 20 is slipped over the projecting end of the plug 15 carrying the wire 17, and the head 21 is slipped over the head of the screw 16, as shown in Fig. 3. The medial portion of the strip fits around one side of the head 12, and the flanges 23 and 24, which now meet, fit the opposite side and also the top and bottom of the head, the parts fitting the bottom being clear of the post 11. It will therefore be seen that the terminal is now completely covered, and corrosion is reduced to a minimum or entirely eliminated. As the outer end of the tubular head 20 is open, the wire 17 can project therefrom as shown in Fig. 3.

I claim:

1. A terminal protector comprising a strip of pliable material having tubular heads projecting from one side thereof at the ends, and provided with outstanding marginal flanges on its opposite side extending around the ends thereof, and along the sides, the flanges of the respective ends of the strip being spaced, said strip being bendable in a direction to bring the flanges in edgewise contact and the heads in alinement.

2. A terminal protector comprising a strip of pliable material having tubular heads projecting from one side thereof at the ends, and provided with outstanding marginal flanges on its opposite side extending around the ends thereof, and along the sides, the flanges of the respective ends of the strip
- 5

being spaced, said strip being bendable in a direction to bring the flanges in edgewise contact and the heads in alinement, and one of the aforesaid heads being open at its outer end.

In testimony whereof I affix my signature.
MICHAEL LA ROCCO.
